UNITED STATES PATENT OFFICE.

FLORIAN BUSCH, OF NEW YORK, N. Y.

IMPROVEMENT IN POCKET-BOOKS.

Specification forming part of Letters Patent No. 123,232, dated January 30, 1872.

To all whom it may concern:

Be it known that I, FLORIAN BUSCH, of the city, county, and State of New York, have invented a new and useful Improvement in Pocket-Books; and I do hereby declare the following to be a full, clear, and exact description thereof, which will enable those skilled in the art to make and use the same, reference being had to the accompanying drawing forming part of this specification, in which drawing—

Figure 1 represents a plan of my pocket-book when the same is unfolded, some parts being broken away so as to illustrate the entire construction. Fig. 2 is a transverse section of the same.

Similar letters indicate corresponding parts.

This invention relates to a pocket-book, the body of which is made in two parts, connected by elastic straps or bands in such a manner that the same can be extended and accommodated to the quantity of papers contained in the same. My book is also provided with bill-retaining flaps connected to the body of the book by means of elastic straps or bands, so that said flaps, when brought to bear upon a pile of bills or papers, will accommodate themselves to the thickness of said pile; and, furthermore, said flaps can be readily turned back for the introduction or removal of said bills or papers.

In the drawing, the letter A designates the body or envelope of my pocket-book, which is composed of two parts, B C, connected together by elastic straps or bands *a*, so that said body or envelope can be extended according to the quantity of papers or bills to be placed into the book, the part B being made to extend over the straps or bands *a*, so as to conceal the same and to preserve a uniform appearance of the book. In the interior of the part C of the envelope A is formed a pocket,

b, for the reception of bills or papers of any kind, and to the part B are secured two flaps, *c c*, being connected to the envelope by elastic straps or bands *d d*, so that the same can be turned back for the reception of bills or papers, or that they can be turned in over the edges of said bills or papers, as shown in the drawing. By means of their elastic connection said flaps are enabled to accommodate themselves to the thickness of the pile of bills or papers placed beneath them and to bear down thereon with sufficient force to prevent the same from becoming displaced or from dropping out if the book is opened. By turning back one of these retaining-flaps easy access can be had to the bills or papers, while the other flap retains said bills or papers with sufficient tenacity to prevent them from being blown away or from becoming displaced by accident.

In the drawing I have shown the retaining-flaps bearing down upon the long sides of a pile of bills placed beneath them; but it will be readily seen that said retaining-flaps could be arranged on the short sides or ends of the bills or of the pile of papers placed beneath them.

What I claim as new, and desire to secure by Letters Patent, is—

1. A pocket-book having an expanding body or envelope, composed of two parts, connected by elastic bands or straps, substantially as herein shown and described.

2. The retaining-flaps *c c*, connected to the body of a pocket-book by elastic bands or straps *d d*, substantially in the manner and for the purpose set forth.

FLORIAN BUSCH.
